UNITED STATES PATENT OFFICE

VICTOR E. GASSEK AND LEONIDES J. GASSEK, OF MADISON, WISCONSIN

COLLAPSIBLE TUBE CAP

Application filed March 8, 1932. Serial No. 597,576.

This invention relates to collapsible tubes for liquids and semi-liquids and more particularly to closures therefor and has for the primary object, the provision of a device of the above stated character whereby the contents of the tube may be easily dispensed therefrom without undue obstruction and obviates the loss of the closure or the necessity of attaching to and detaching the closure from the tube.

Another object of this invention is the provision of a slidable closure so attached to the tube and the latter so constructed as to conform thereto, whereby the tube may be easily and quickly opened or closed and the discharge port and surrounding surfaces of the tube to said port may be kept clean of the contents of the tube, rendering the device sanitary and providing an efficient seal for the tube for preventing evaporation of the contents or foreign matter coming in contact therewith.

With these and other objects in view, this invention consists in certain novel features of construction, combination and arrangement of parts to be hereinafter more fully described and claimed.

For a complete understanding of our invention, reference is to be had to the following description and accompanying drawing, in which

Figure 1 is a side elevation illustrating a collapsible tube and closure therefor constructed in accordance with our invention.

Figure 2 is a fragmentary vertical sectional view illustrating the same with the closure shown in an opened position in full lines and in a closed position in dotted lines.

Figure 3 is a view similar to Figure 2 taken at right angles to Figure 2.

Figure 4 is a top plan view illustrating the device.

Figure 5 is a perspective view illustrating the closure.

Referring in detail to the drawing, the numeral 1 indicates a collapsible tube for containing liquids or semi-liquids and has one end sealed by suitable fasteners 2 so that the contents may be readily placed in the tube initially. The opposite end of the tube is

closed by an integral head 3 of semi-spherical shape having formed upon its outer face and at one side thereof a flattened wall 4 terminating at one edge in an abrupt shoulder 5. The head 3 is provided with a discharge port 6 of any suitable shape opening outwardly through the flat face 4 whereby the contents of the tube may be dispensed in the usual manner by squeezing or placing pressure upon the tube.

A groove or channel 7 is formed on the outer face of the head 3 and has one end in communication with the flat face 4 and its other end terminating in an abrupt shoulder 8 disposed opposite to the shoulder 5. A closure 9 is slidably mounted in the channel or groove 7 and has one face thereof concaved as shown at 10 to conform to the contour of the outer face of the head 3.

The closure 9 in its outer wall is provided with a groove 11 for receiving a bail 12, the ends of which are received in sockets 13 formed in opposite sides of the tube or the head thereof. The bail 12 is constructed of resilient material and is offset intermediate its ends as shown at 14 with the offset fitting within the groove 11 so as to slidably secure the closure in the groove or channel 7. The closure 9 is provided with oppositely inclined knurled faces 15 located at opposite sides of the groove 11 whereby a person by placing a finger or thumb against one of the knurled faces may move the closure in one direction and then in an opposite direction when pressure by the thumb or finger is placed on the other knurled face.

With the closure 9 positioned in the groove or channel with one end in engagement with the shoulder, the port 6 is uncovered so that the contents of the tube may be dispensed as desired. By sliding the closure in the groove or channel until its opposite end engages the shoulder 5, the port 6 is closed and the contents of the tube sealed from evaporation and foreign matter; thus it will be seen that it is possible to open and close the port without detaching the closure from the head 3.

By having the port opening outwardly through the flat face 4 allows the contents when said port is uncovered to be easily dispensed without obstruction. Referring to Figure 5 it will be

noted that the ends of the closure 9 are provided with sharpened edges 16 which are adapted to scrape any foreign matter or dried contents of the tube from the face 4 about 5 the discharge port so as to maintain the device in a highly sanitary condition.

The bail 12 is substantially U-shaped, the free ends of which are bent angularly to form trunnions 17 fitting within the sockets 13 to 10 pivotally connect the bail to the head, also permitting the bail to be detached from or attached to the head when desired by flexing the arm portions of the bail. The head 3 upon its outer face and upon opposite sides 15 thereof is provided with tapering grooves 17' leading to the sockets 13 for the purpose of guiding or directing the trunnions 17 into the sockets during the initial application of the bail to the head.

20 While we have shown and described the preferred embodiment of our invention, it will be understood that minor changes in construction, combination and arrangement of parts may be made without departing from 25 the spirit and scope of our invention, as claimed.

Having thus described our invention, what we claim is:

1. A collapsible tube comprising a collapsible body, a semi-spherical shaped head for 30 said body and having a port adjacent one edge, said head having a groove and a flattened face in communication with the groove and surrounding the port, said flattened face 35 and groove forming oppositely disposed abrupt shoulders, and a closure slidably mounted in the groove and movable to close the port and limited in its movement by the shoulders.

2. A collapsible tube comprising a collapsible body, a semi-spherical shaped head on 40 the body and having a port adjacent one edge, said head having a groove and a flattened face in communication with the groove and surrounding the port, a closure having 45 a curved face slidably mounted in the groove and upon the flattened face, and means pivotally connecting the closure to the head.

3. A collapsible tube comprising a collapsible body, a semi-spherical shaped head on 50 the body and having a port adjacent one edge, said head having a groove and a flattened face in communication with the groove and surrounding the port, a closure having a curved face slidably mounted in the groove 55 and upon the flattened face, and a bail connected to the closure and pivoted to the head.

4. A collapsible tube comprising a collapsible body, a semi-spherical shaped head on the body and having a port adjacent one edge, 60 said head having a groove and a flattened face in communication with the groove and surrounding the port, a closure having a curved face slidably mounted in the groove and upon the flattened face, said head having 65 oppositely disposed sockets with grooves

communicating therewith and extending toward the first named groove, a substantially U-shaped bail having angularly disposed ends journalled in said sockets and guided therein by the second named grooves, said closure having a groove to receive the bail. 70

5. A collapsible tube comprising a collapsible body, a semi-spherical shaped head on the body and having a port adjacent one edge, said head having a groove and a flattened face in communication with the groove and surrounding the port, a closure having a curved face slidably mounted in the groove and upon the flattened face, said head having oppositely disposed sockets with grooves communicating therewith and extending toward the first named groove, a substantially U-shaped bail having angularly disposed ends journalled in said sockets and guided therein by the second named grooves, said closure having a groove to receive the bail, said bail having an offset portion fitting within the last named groove. 80

6. A collapsible tube comprising a collapsible body, a semi-spherical shaped head on the body and having a port adjacent one edge, said head having a groove and a flattened face in communication with the groove and surrounding the port, a closure having a curved face slidably mounted in the groove and upon the flattened face, said head having oppositely disposed sockets with grooves communicating therewith and extending toward the first named groove, a substantially U-shaped bail having angularly disposed ends journalled in said sockets and guided therein by the second named grooves, said closure having a groove to receive the bail, said bail having an offset portion fitting within the last named groove, said closure having oppositely disposed knurled faces arranged on the opposite side of the groove of said closure. 90

100 In testimony whereof we affix our signatures.
